(57) **CLAIM**

The ornamental design for a kitchen scale with removable cover or plate, as shown and described.

DESCRIPTION

FIG. 1 is a perspective view of a kitchen scale with a removable cover or plate embodying our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a perspective view of a kitchen scale with a removable cover or plate of FIG. 1 showing the cover or plate in a removed position.
